UNITED STATES PATENT OFFICE.

MATTHEWS FLETCHER, OF INDIANAPOLIS, INDIANA.

METHOD AND MEANS OF MIXING CONCRETE.

Application filed July 14, 1925. Serial No. 43,631.

To all whom it may concern:

Be it known that I, MATTHEWS FLETCHER, a citizen of the United States, residing at Indianapolis, in the county of Marion and State of Indiana, have invented certain new and useful Improvements in Methods and Means of Mixing Concrete, of which the following is a specification.

My invention relates to a method of mixing concrete and a mechanism for carrying out such method and it is an object thereof to provide a device in which the process of mixing shall be a rapid and violent stirring action applied to a rapid and continuous succession of small batches of materials in place of the customary process of mixing in which slow tumbling and stirring action is applied to a slow repetition of comparatively large batches of materials.

The common method of producing concrete by machine is to load a batch of ingredients into a slowly revolving cylinder or drum where the mass is mixed by tumbling, discharged, and the process repeated with another batch. The drum must revolve slowly in order to prevent simply whirling the mass without mixing, and consequently the time required to thoroughly mix a batch is practically the same for large and small machines. The advantages of rapid and violent agitation to secure intimate mixing and adhesion of cement are well known, but heretofore these advantages have not been obtained generally in a portable machine of commercial capacity on account of the structural and mechanical difficulties attending the rapid and violent agitation of the heavy semi-liquid mixture of concrete in large quantities. My method contemplates overcoming these difficulties by greatly reducing the size of the batch or unit of production, assembling a rapid succession or continuation of batches, and rapidly mixing them in and discharging them from a small machine of violent action.

Among other advantages of my method and device may be mentioned the fact that they produce an intimate mixing and adhesion of cement to other particles with consequent density and strength in the ultimate concrete, the fact that they provide for accurate control of the proportions of the materials entering into the mixture, the fact that they provide for the commingling of

the solid materials in predetermined constant proportion before entering the final mixing process, and the fact that they provide for the production of concrete mixture in a practically uninterrupted flow with consequent large average output per unit of time.

Referring to the accompanying drawings which are made a part hereof and on which similar reference characters indicate similar parts,

Figure 1 is a plan of a mechanism constituting a preferred embodiment of my invention,

Figure 2, a side elevation partly in section,

Figure 3, a section on line 3—3 of Fig. 1,

Figure 4, a detail of a part as seen from the right in Figure 3,

Figure 5, a section at right angles to Figure 3 with modifications of certain parts, and

Figure 6, a fragmentary section on line 6—6 of Figure 5.

In the drawings reference characters 10, 11 and 12 indicate separate bins for different solid ingredients, said bins being indicated in the present embodiment of the invention and for the present purpose, as containing respectively, sand, gravel and cement.

Each bin is shown as having an outlet at its lower end as indicated at 13 by means of which the material in the corresponding bin is permitted to flow down upon the upper run of a conveyor belt 14 in a continuous stream, and this material forms a continuous ridge or stream on the belt in the channel between two of a series of partitions or walls 15 supported above and extending along the belt 14. Each of the channels between pairs of partitions 15 is provided with a gate 16 adjustable vertically and held in position by any suitable means, which gates serve to limit adjustably the amount of material which will move forward with the conveyor in the respective channels, thereby providing a means of proportioning the materials in any ratio desired. The number and arrangement of bins, the inclination of the conveyor, the distance the conveyor travels and all such minor details may be varied to suit particular circumstances or preferences.

Another conveyor 17, which may conveniently be referred to as a sweeper, is pro-

vided adjacent to the forward end of the conveyor 14 and this secondary conveyor or sweeper is provided with brushes or blades 18 at suitable intervals in its length and so placed and guided that the brushes or blades or similar suitable devices 18 will travel in a constant path across the upper run of the primary conveyor 14 and along a trough 20 (Fig. 3) extending beyond its edge, thereby carrying batches of commingled materials off the primary conveyor, through the trough 20 and into the hopper 21. In this way, it will be seen that the brushes take a cross section of each stream of material and so carry suitable increments of all materials which make up the mixture. The sweeper 17 is regarded as carrying successive small batches of commingled materials to hopper 21 where they may be allowed to accumulate in a mass the ingredients of which are nearly uniformly proportioned throughout. Or it might be regarded as operated step by step and provided with more positive batch-conveying means whereby the successive small batches would be more or less independently fed to a mixing device or series of devices. A pipe 22 with a valve 23 provides a means of adding water to the materials in the hopper 21.

30 A mixing device suitable to accomplish the final mixing of the commingled solids with water or other suitable liquid is located beneath an opening in the bottom of hopper 21. My mixing device consists of a vertical passage or chamber formed by a stationary casing 24 which forms with the hopper a device shaped approximately like an hour-glass and is of circular cross section. In this chamber an agitator 25 is rapidly revolved by means of a shaft 25 which preferably is concentric with the vertical axis of the chamber and which may enter the chamber from above through the opening in the bottom of hopper 21 without the necessity of providing a stuffing-box, all as shown in Figs. 2, 3 and 5. The chamber is open at the top to receive the mass or batches of materials from the hopper and it extends downward to an open bowl or pan 27 provided to catch the mixture and thereby retard its rate of flow through the mixing chamber above in order that it may be retained long enough to be subjected to thorough stirring by the agitator 25. The pan 27 is provided with an overflow spout 28 in the side or rim, or means may be provided for removing the mixture at the desired rate by intermittently tilting the pan or by undermining by means of a conveyor 30 which may operate on the mass through an opening in the pan 27 at the bottom of the mixing chamber as shown by Fig. 5. The cross sectional area of the mixing chamber may be constant throughout its length as in a straight tube or it may be varied, pref-

erably increasing from top to bottom as shown. The agitator 25 consists of a series of blades, paddles, or irregularities 29 which can be rapidly revolved about a vertical axis concentric with the axis of the chamber. 70 The surfaces of the blades may be warped or formed into the shape of a screw to exert a vertical pressure upon the mixture in addition to the stirring action, and such a screw may extend up into the hopper 21 to 75 provide a positive means of feeding the mass into the mixer, all as shown.

In the use of my device the materials are placed in separate hopper bins from which they pass to separate channels or chutes the 80 bottoms of which are formed by a moving conveyor belt, apron or platform which drags or pushes the materials through the channels and under gates or scrapers which are adjusted to limit the quantities that will 85 emerge in constant proportion and will follow on the conveyor in continuously formed parallel streams.

The parallel streams of materials in constant proportion are carried forward by the 90 conveyor from which a cross section or batch of them is swept or pushed at intervals by a series of flexible or pliant brushes or blades moved by a belt or wheel revolving transversely to the direction of the streams, and 95 the batches thus formed are swept or pushed off of the conveyor and into a hopper.

The batches of solid ingredients in predetermined proportion enter either intermittently or continuously into the hopper 21 into which the liquid ingredient (as water) also flows, and from which the mass flows through a mixing chamber 24 where it is violently agitated and mixed as it flows by a series of rapidly revolving blades preferably revolving on a vertical axis concentric with the vertical axis of the mixing chamber. The mixture is kept from simply falling through the chamber, with consequent separation of the particles, by the pan or 100 bowl 27 which being placed beneath the bottom opening of the mixing chamber tends to support the mixture in the chamber and 105 retards its rate of flow enough to allow time for proper mixing. The pressure exerted by the weight of incoming batches, which 110 pressure may be increased by the downward pressure exerted by the screw-shaped agitator, causes the finished mixture to flow or (to use a word that recently has come into 115 general use to accurately describe the action) to "slump" over the edge or brim of the pan at the overflow spout. In place of the slump process of discharging the finished mixture, a more positive means of discharging by 120 undermining the mixture, or by intermittently tilting the pan may be provided and suitably synchronized. The arrangement of an agitator revolving on an axis concentric with 125 the vertical axis of a mixing chamber of 130

circular horizontal section allows of a very rapid rate of rotation of the agitator without piling up the mixture to one side (as occurs where an agitator is revolved rapidly on a horizontal axis) and consequently the materials can be subjected to very forceful stirring which causes the particles to collide with and impinge upon each other with great violence and thereby to tend to adhere to each other and to become thoroughly and intimately mixed in a very short time. The screw-shaped agitator and the "flared" chamber provide additional means by which even "stiff" mixtures (that is, mixtures containing little or no excess water) may be forced through the mixing process. Thus is produced an intimate mixing and adhesion of cement with consequent density and strength in the ultimate concrete.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:

1. A method of mixing concrete which consists in simultaneously and continuously moving sundry ingredients in small parallel streams, disposed laterally with relation to each other, and moving forward portions of the mass transversely of the path of movement of the streams to mix and discharge the same, substantially as set forth.

2. A continuous process of mixing concrete or the like by producing continuous slowly moving parallel streams of different solid ingredients, and simultaneously horizontally and transversely mixing and feeding cross sectional increments of each stream into a mixing chamber, substantially as set forth.

3. The combination in a concrete mixing machine of a hopper having a plurality of partitions forming a plurality of bins, and a conveyor disposed beneath said hopper for receiving parallel streams of solid material of different character therefrom, substantially as set forth.

4. The combination in a concrete mixing machine of a hopper having a plurality of partitions forming a plurality of bins, a conveyor disposed beneath said hopper for receiving parallel streams of solid material of different character therefrom, means for feeding batches of material comprising a cross section of each stream simultaneously into a chamber, means for adding water thereto, and a rotary agitator in the chamber, substantially as set forth.

5. A concrete mixer as in claim 3, with

independent means for adjusting the feed of solid material in each stream, substantially as set forth.

6. A concrete mixer as in claim 3, comprising a conveyor belt for supporting all of said streams of solid material, substantially as set forth.

7. A concrete mixer as in claim 3, comprising a conveyor belt for supporting all of said streams of solid material, and means 75 for keeping the parallel streams separate, substantially as set forth.

8. A concrete mixer comprising a plurality of bins for solid material, means for feeding material in parallel horizontal 80 streams from the respective bins, guiding means for separating the streams from each other, gates for regulating the flow of material in said streams, and a mixing chamber for receiving such material, substantially 85 as set forth.

9. A concrete mixer as in claim 8, the spaces between the guides being open at the top for a part of their length for convenient 90 inspection, substantially as set forth.

10. A concrete mixer as in claim 8, having a common conveyor for moving said streams in synchronism, substantially as set forth.

11. A concrete mixer comprising means 95 for feeding solid material in parallel streams, a conveyor movable transversely of the path of said streams, a mixing chamber to which said conveyor carries increments of material from each of said streams, means for supplying water to said mixing chamber, and agitating means for the mixture, substantially 100 as set forth.

12. A concrete mixer comprising a conveyor for feeding solid material in parallel 105 streams, a sweeper movable transversely of the path of said streams, brushes on the sweeper, a mixing chamber to which said sweeper carries increments of material from each of said streams, means for supplying 110 water to said mixing chamber, and agitating means for the mixture, substantially as set forth.

13. A concrete mixer comprising means for feeding a parallel series of streams of solid material of different characteristics, a conveyor movable transversely of said feeding means, a trough in which said conveyor travels, a mixing chamber at the farther end of the trough, means for feeding water to 115 the mixing chamber, and a rotary agitator in the mixing chamber, substantially as set forth.

14. A concrete mixer comprising means for feeding solid material in parallel streams, and conveying means movable transversely of the path of said streams for collecting material from each, substantially as set forth.

15. A method of mixing concrete comprising providing continuously moving streams 120

of different solid ingredients, simultaneously damming the ingredients and commingling said dammed ingredients by moving them in a sidewise direction, substantially as set forth.

16. A method of mixing concrete comprising providing continuously moving streams of different solid ingredients, simultaneously damming the ingredients and commingling said dammed ingredients by moving them in a sidewise direction, and thereafter rapidly and violently agitating the commingled ingredients by passing them in contact with rapidly rotating blades, substantially as set forth.

17. A process of mixing concrete comprising feeding relatively small batches of the ingredients into a hopper and downwardly past an upright rotating screw conveyor,

means below the hopper retaining a predetermined quantity of the mixture in the hopper at all times, and discharging a predetermined quantity of the mixture from the hopper by a slumping action upon the application of a corresponding amount of the ingredients in the entrance end of the hopper, substantially as set forth.

18. A conveyor comprising a belt having a continuous row of brushes at one side and a series of spaced brushes extending across the belt from said continuous brushes, substantially as set forth.

In witness whereof, I have hereunto set my hand and seal at Indianapolis, Indiana this 6th day of July, A. D. nineteen hundred and twenty-five.

MATTHEWS FLETCHER. [L. S.]
